FRONT PANEL FOR A WALL MOUNTED OVEN

Thomas R. Field, Indianapolis, Ind., assignor to Jenn Air Products Company, Inc., Indianapolis, Ind., a corporation of Indiana

Filed Aug. 21, 1963, Ser. No. 76,305

Term of patent 14 years

(Cl. D81—25)

Fig. 2.

Fig. 1.

FIG. 1 is a perspective view of a front panel for a wall mounted oven embodying my new design.

FIG. 2 is a sectional view taken generally along the line 2—2 of FIG. 1.

The broken line disclosure in FIG. 1 is for illustrative purposes only.

I claim:

The ornamental design for a front panel for a wall mounted oven, as shown and described.
